UNITED STATES PATENT OFFICE.

WALTER KENNEDY, OF PITTSBURGH, PENNSYLVANIA.

UNIVERSAL COUPLING.

1,139,125.

Specification of Letters Patent. Patented May 11, 1915.

Application filed September 21, 1914. Serial No. 862,880.

To all whom it may concern:

Be it known that I, WALTER KENNEDY, residing at Pittsburgh, in the county of Allegheny and State of Pennsylvania, a citizen of the United States, have invented or discovered certain new and useful Improvements in Universal Couplings, of which improvements the following is a specification.

The invention described herein relates to certain improvements in couplings for connecting rotatable parts driven one by the other, the coupling being so constructed as to permit of one of the parts being shifted out of alinement with the other part, while maintaining operative engagement with the latter.

The invention is hereinafter more fully described and claimed.

In the accompanying drawings forming a part of this specification, Figures 1 and 2 are elevations at right angles one to the other of my improved coupling; Figs. 3 and 4 are sectional views of the same, the planes of section being indicated by the lines III—III and IV—IV Fig. 5; Fig. 5 is a transverse section through the coupling; Fig. 6 is a perspective view of the intermediate or connecting block; Figs. 7 and 8 are views similar to Figs. 3 and 4 illustrating a modification of the coupling, and Fig. 9 is a transverse section on a plane indicated by the line IX—IX Fig. 8; Figs. 10 and 11 are sectional views taken on planes at right angles to each other illustrating certain modifications.

While the invention described herein is shown as connecting the neck of a roll with its driving spindle, it will be understood that the improvement is equally adapted for connecting any driving and driven rotatable parts. As shown in Figs. 1 and 4 the spindle or shaft 1 is provided at its end with diametrically arranged lugs 2 projecting substantially parallel with the axis of the shaft. These lugs 2 extend into radial notches 3 formed in the periphery of the block 4. As in the use of the coupling, the shaft or roll are designed to be shifted to angular relation to each other, the inner walls of the lugs are inclined outwardly in both directions from points adjacent to their outer ends as clearly shown in Fig. 4, thereby forming edges *a* on which the parts move. The roll or driven member 5 is provided with a rib 6 arranged diametrically across the end of the neck of the roll. This rib

extends into a groove 7 formed in one side of the block and extending diametrically across the block at right angles to the notches 3. As will be seen by reference to Figs. 1, 2, 3 and 6, the side of the block in which the groove is formed is inclined in opposite direction from a diametric line at right angles to the groove and the rib 6 is somewhat shorter than the depth of the groove, so that the block can oscillate on the ridge *b* or apex of the inclined surfaces of the block.

In order to prevent the block from moving transversely out of engagement with the rib, a pin 8 is passed through the side walls of the groove in the block and through the rib 6, the hole in the rib being made sufficiently larger than the pin to permit of the angular shifting of the block. As it is generally impracticable to disengage the coupling members by a longitudinal movement of the parts connected, a hole 9 is formed through one or both of the lugs 2 to permit of the insertion and removal of the locking pin.

As shown in Figs. 7, 8 and 9 the construction above described may be reversed, that is to say the lugs 2 may be formed on the roll or driven member 5 and the diametric rib 6 on the shaft or driving member, and in lieu of the transversely arranged locking pin 8, a longitudinally removable bolt 10 may be employed for locking the block and rib together transversely. As shown in Figs. 7 and 8, the rib is notched and an axial hole is formed longitudinally in the part carrying the rib for the reception of the locking bolt. Through the wall 12 forming the bottom of the groove 7 is formed an opening for the reception of the end of the bolt, said opening being made larger than the bolt in a direction parallel with the groove so that the bolt when in engagement with the block will not interfere with the angular shifting of the latter. The bolt can be shifted into and out of engagement with the block by a pin 13 arranged in a slot 14 and engaging the bolt.

In Figs. 10 and 11, the pin 8 holding the block 4 and rib 6 in operative relation is provided with a head and at its opposite end with a stem 15 which extends into a recess 16 in one of the lugs 2. This stem is threaded for the reception of a nut 17 and between the bottom of the recess 16 and the nut is interposed a spring 18. As the ten-

sion of the spring will draw the block 4 into contact with one of the lugs 2, the edge or apex α forming the center of movement between the block 4 and the part or member 1 having the lugs 2 can be formed on the bottom of the groove in the block into which such lug extends.

My improved coupling has the surfaces of the several parts which are intended to 10 slide one on the other finished, so that said surfaces may closely contact thus avoiding lost motion. It is preferred to form the bearing surfaces of the lugs and rib by plates of brass or other suitable metal detachably secured to said parts.

No claim is made herein specifically to the construction shown in Figs. 7, 8 and 9 as such construction *per se* forms the subject-matter of another application.

20 It is characteristic of my improvement that the lugs and the rib on the parts or members to be connected overlap and that portions of the member or block through 25 which motion is transmitted are interposed between these overlapping lugs and rib. By reason of such construction the transmitting block is subjected to pressure and not to any material torsional strain.

I claim herein as my invention:

30 1. A coupling comprising driving and driven rotatable parts, one of said parts having lugs and the other part being provided with a rib extending across its end, in combination with a block provided with 75 peripheral notches for the reception of said lugs and with a groove for the reception of said rib, the lugs and rib slidably bearing against the side walls of the notches and groove and the lugs movable longitudinally 80 in the notches to permit of the driving or driven parts being shifted to angular position one to the other.

2. A coupling comprising driving and driven rotatable parts, one of said parts hav-

ing lugs and the other part being provided 45 with a rib extending across its end, in combination with a block provided with peripheral notches for the reception of said lugs and with a groove for the reception of said rib, the lugs and rib slidably bearing against 50 the side walls of the notches and groove, and means for locking the block against lateral movement along the rib.

3. A coupling having in combination a block, driving and driven parts provided 55 with projecting portions adapted to positively engage the block in planes at right angles to each other, the projecting portion of one part overlapping the corresponding portion of the other part and including between them portions of the block, the projecting portions being movable independently of the block in directions substantially at right angles to the direction of rotation of the coupling and a pin engaging the 65 block and a portion projecting into engagement with the block.

4. A coupling having in combination driving and driven rotatable parts, a connecting block, the driving and driven parts 70 having portions projecting therefrom and positively engaging the block in planes at right angles to each other, said parts being movable to angular positions relative one to the other while maintaining engagement 75 with the block, one of said parts being movable relative to the block in the direction of the axis of rotation of said part, and means for preventing the block from moving relative to the other part in the direction of the 80 axis of rotation of said part.

In testimony whereof I have hereunto set my hand.

WALTER KENNEDY.
